UNITED STATES PATENT OFFICE.

DAVID SHECHTMAN AND RALPH FEINMAN, OF NEW YORK, N. Y.

SUPPORTING AND LOCKING DEVICE.

Application filed June 20, 1925. Serial No. 38,487.

This invention relates to supporting and locking devices. An object of the invention is to provide an improved practical device for locking bottles, containers, or the like thereto or for suspending articles therefrom.

Another object of the invention is the provision of a device of the character described comprising few and simple parts, which is neat in appearance, adapted to be collapsed into a compact compass when not in use, very cheap to manufacture, and practical and efficient to a high degree for the purposes described.

Other objects of the invention will in part be obvious and in part hereinafter pointed out.

The invention accordingly consists in the features of construction, combinations of elements and arrangement of parts which will be exemplified in the construction hereinafter described, and of which the scope of application will be indicated in the following claims.

In the accompanying drawing, in which is shown one of the various possible illustrative embodiments of this invention:

Figs. 1 and 2 are perspective views of a device embodying the invention constructed to retain a bottle in a releasably locked position, Fig. 1 showing portions of the casing partly broken away to expose the interior construction;

Fig. 3 is a cross-sectional view taken on line 3—3 in Fig. 1; showing the means for mounting the casing of the device to the base plate;

Fig. 4 is a fragmentary detail view of the lock detent means;

Figs. 5 and 6 are sectional views showing modified forms of the device embodying the invention; and

Fig. 7 is a fragmentary view showing the arm of the device formed with a closure cap. Referring in detail to the drawing, 10 denotes a bottle locking device embodying the invention which is adapted to be secured to a vertical wall 11 at a suitable distance above the ground or floor 12 for engaging the neck 13^a of a bottle 13 standing on the floor as shown in Figs. 1 and 2.

Said device 10 may be made of cast or pressed metal and is seen to comprise a base or supporting plate 14 having rigidly secured thereto a casing 15. In said casing there is mounted a mechanism 16 which is

adapted to lockingly co-operate with a suitably shaped arm 17, the latter being swingably supported to extend through an opening 15^a in the casing 15 for engaging over 69 the neck 13^a of a bottle.

The plate 14 is secured to the wall by any suitable fastening means such as screws 18 and is provided with a plurality of slots 14^a which are constructed to receive and interlock with the anchoring tabs 19 projecting from the side walls of the casing 15 for fixedly mounting the latter on said plate when the tabs 19 are fully inserted into the slots 14^a as shown in Fig. 3.

The locking mechanism 16 may comprise a member 20 of substantially U-shaped cross-section which may be pivotally mounted to the bottom side of the casing 15 by means of a rivet 21 passing through the bright portion 20^a of said member. One upstanding portion 20^b of the member 20 is positioned to swing across the path of movement of the inner free end 17^a of the arm 17 and is provided with any suitable means, as for example the bifurcation 22, for engaging the end 17^a of said arm and for releasably locking the latter in a normally horizontal position, as shown in Figs. 1 and 2.

To lock or unlock the mechanism 16, there are provided in the side of the casing 15, in alignment with said portion 20^b, and with the other portion 20^c of member 20, narrow apertures 23 and 24 wherein a key (not shown) may be inserted for swinging the member 20 in and out of engagement with the arm end 17^a.

To provide against the accidental disengagement of the mechanism 16 with the arm 17 when the latter is in effective locking position, a suitable spring detent 26 mounted in the casing 15 may be provided for releasably engaging with a notch 27 in the portion 20^b of member 20 (see Figs. 1 and 4) said detent being adapted to slip 100 in and out of said notch when the member 20 is swung about its pivot on inserting a key in said apertures 23 and 24 respectively. Stop pins 28 supported on the inside of casing 15 may be provided for limiting the 105 swinging movement of member 17 as shown in Fig. 1.

The arm 17 is adapted to swing in trunnion bearings 25 mounted on the inner side of the casing 15 adjacent the opening 15^a to 110 co-operate with an offset portion 17^b of the arm 17 for permitting the exterior or

engaging end 17^c of said arm to be compactly collapsed when not in use as shown in the dotted lines in Fig. 1. The engaging end 17^c may be of any suitable shape and as here shown forms a ring or annulus adapted to fit over the neck end of the bottle 13.

In using the invention, the device 10 is mounted in position on the wall 11, as shown in Figs. 1 and 2. The locking mechanism 16 is next released by inserting a key into 10 the aperture 23 to swing the member 20 free from arm 17 so as to permit the free vertical swing of said arm.

The neck 13^a of the bottle may then be 15 fitted through the ring end 17^c of the arm and the latter locked in a normally horizontal position by inserting a key into the aperture 24 to swing the bifurcation 22 on member 20 to engage the end 17^a of arm 17 thus 20 locking the bottle 13 to the device 10. The detent 26 then is in position to engage with the notch 27 and serves to retain the member 20 against disengagement through any causes or means except the insertion of a 25 proper key in the aperture 23. The key when so inserted is pressed on portion 20^c of the member 20 swinging the latter about its pivot simultaneously slipping the detent 26 from the notch 27 and releasing said member 20 from the arm end 17^a.

If desired a cap 27 may be provided over 30 the ring end 17^c of arm 17 to form a closure for the mouth of the bottle 13. Said cap may be rigidly fastened to the arm 17 or 35 may be made integral therewith as shown in Fig. 7.

Fig. 5 shows a modified form of device 40. Here a sliding bar 30 replaces the swinging member 20 shown in Fig. 1, said bar being mounted on a suitable bearing 31 supported in the casing 15. A pin 32 passes through a slot portion 30^a in the bar 30 for retaining the latter in proper operative position. Extending from said bar is 45 a latch projection 30^b which corresponds to the portion 20^b of the member 20 shown in Fig. 1. By reciprocating the bar 30 by means of a key inserted in apertures 23 and 24, the arm 17 may either be locked in a 50 horizontal position or released to permit the swinging thereof in the same manner as in the construction already described above.

The device 10 may also be adapted to 55 serve as a means for suspending articles in the kitchen and for other like purposes.

When so used, no keys are necessary and the ends 20^b and 20^c in the form shown in Fig. 1, and bar 30 shown in Fig. 5 may be made long enough to extend through the casing 60 15. A modified form applied to the sliding construction is shown in Fig. 6. Here the bar 30, as shown in Fig. 5 is replaced by a longer bar 40 having end portions 40^a and 40^b extending through the opposite side of 65 the casing 15. In this latter form the arm

47 corresponding to arm 17 in Fig. 5 may be provided with a sleeve or bayonet joint 47^a to permit the interchanging of various shaped engaging ends 47^c in the well known manner.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or 80 shown in the accompanying drawing is to be interpreted as illustrative and not in a limiting sense.

Having thus described our invention, we claim as new and desire to secure by Letters 85 Patent:—

1. In a device of the character described, a casing having an opening, an arm supported to swing in a vertical plane and extending through said casing opening, 90 adapted to retain objects thereto and a mechanism in said casing including a member movable in a horizontal plane in the path of movement of said arm for releasably interlocking with the latter.

2. In a device of the character described, a casing, an arm pivoted on the inner side of the casing for vertical movement, an end of the arm extending into the casing beyond the pivot, a ring portion terminating the 100 other end of said arm on the exterior side of the casing adapted to engage the neck of a bottle and horizontally movable means for releasably holding the first mentioned end of said arm against swinging movement for locking the bottle to the device.

3. In a device of the character described, a casing, an arm pivoted on the inner side of the casing for vertical movement, an end of the arm extending into the casing beyond the pivot, a ring portion terminating the other end of said arm on the exterior side of the casing adapted to engage the neck of a bottle horizontally movable means for releasably holding the first mentioned end of said arm against swinging movement for locking the bottle to the device, and a cup formed over said ring portion to serve as a closure for the bottle.

4. In a device of the character described, a casing having an opening, and an arm swingably supported to extend through said opening, the end of said arm on the exterior side of the casing having means for detachably interchanging various forms of object 115 engaging portions.

In testimony whereof we affix our signatures.

DAVID SHECHTMAN.
RALPH FEINMAN.
